(57) **CLAIM**

The ornamental design for a “tightening latch for car seat,” as shown and described.

DESCRIPTION

FIG. 1 is a perspective view of a tightening latch for car seat, showing our new design;

FIG. 2 is a front view thereof;

FIG. 3 is a back view thereof;

FIG. 4 is a right view thereof;

FIG. 5 is a left view thereof;

FIG. 6 is a top side view thereof; and,

FIG. 7 is a bottom side view thereof.

The subject matter shown in dashed lines is for illustrative purposes and forms no part of the claimed design.
